CENTRIFUGAL SWITCH

Royal Lee, Milwaukee, Wis., assignor to Lee
Engineering Research Corporation, Milwaukee,
Wis., a corporation of Wisconsin

Application May 16, 1940, Serial No. 335,461

8 Claims. (Cl. 200—80)

The present invention relates to speed-responsive devices and more particularly to centrifugal switches.

It is an object of the invention to provide an improved centrifugal switch which will operate smoothly and accurately throughout a wide range of speed-settings.

Another object is to provide a centrifugal switch which can be economically manufactured and which has an adequate current-carrying capacity.

The invention further consists in the several features hereinafter described and claimed.

In the accompanying drawing, illustrating certain embodiments of the invention,

Fig. 1 is a sectional elevation showing one form of centrifugal switch constructed in accordance with the invention, the switch being mounted on an electric motor and being adjusted for operation at high speed;

Fig. 2 is a front elevation of the switch;

Fig. 3 is a top view;

Fig. 4 is a bottom view;

Fig. 5 is a sectional elevation taken generally along the line 5—5 of Fig. 1;

Fig. 6 is a side elevation of the switch, parts being broken away and parts being shown in section, and the switch being adjusted for operation at low speed;

Fig. 7 is a side view, partly in section, of a modified form of centrifugal switch, the switch being adjusted for operation at high speed;

Fig. 8 is a front elevation of the switch of Fig. 7, and

Fig. 9 is a top view, similar to Fig. 8, showing another form of centrifugal switch in which the contacts are adapted to engage upon increase of speed.

Referring to the drawing, and more particularly to Figs. 1 to 6, thereof, 15 designates a rotatable shaft, such as the shaft of an electric motor 16 the speed of which is to be controlled or regulated by the switch of the invention. Mounted on the shaft is a rotatable member 17 which comprises a metal hub 18 rigidly carrying thereon a disk 19 of insulating material. The hub 18 is secured to the motor shaft 15 in any suitable manner, as by one or more set-screws 20. Current-collecting elements 21 and 22 are mounted on the rotatable member 17 and are preferably in the form of flat concentric collector rings or disks mounted on one side of the insulating disk 19. As seen in Fig. 1, brushes 23 and 24 bear on the respective collector rings 21 and 22 and are here shown to be carried by the motor frame.

Rigidly secured to the insulating disk 19, by a plurality of rivet-forming studs or posts 25 and cooperating screws 26, is a generally circular, C-shaped frame or plate 27 which is formed of a suitable metal such as duralumin. The studs or posts 25 also serve to secure the outer collector ring, 21, to the insulating disk and to electrically connect the metal frame 27 to this collector ring. The C-shaped frame 27 extends at right-angles to the disk axis and in spaced relation to the disk, and has a gap 28 between its ends. A plurality of contacts 29 are detachably secured to the spaced end portions of the plate 27 in off-center relation to the disk axis and have their contact faces lying in a plane normal to the disk axis. The contact heads are preferably formed of tungsten or other resistant metal. In the present instance, each end portion of the plate is shown to carry two contacts. A balancing segment 30 is secured to the plate 27 at the peripheral region thereof diametrically opposite the contacts 29.

Disposed between the insulating disk 19 and metal frame 27 is a forked, plate-like, oscillatory lever 31 which is hingedly supported on the insulating disk by a pair of rivet-forming posts or studs 32 and cooperating screws 33 engaging the ends of a U-shaped hinge-forming leaf spring 34, the latter being riveted or otherwise secured to side extensions of the lever. The frame 27 is provided with openings 35 for access to the screws 33. The plane of the lever 31 is approximately at right angles to the axis of the disk, and the longitudinal center line of the lever extends diametrically with respect to the disk axis. The posts or studs 32 also serve to secure the inner collector ring, 22, to the insulating disk and to electrically connect the lever to this collector ring. The inner collector ring is further secured to the disk by rivets 36. The lever 31 is formed of a suitable light-weight metal such as duralumin. A plurality of contacts 37 are detachably secured to the free ends of fork arms of the lever 31 and cooperate with the contacts 29 on the metal frame 27, the lever contacts being normally urged or biased against the frame contacts by the hinge spring 34. The effective hinge axis of the lever extends in a transverse direction with respect to the disk axis and at one side of the disk axis, while the contacts 31 are arranged at the opposite side of the disk axis. The lever contacts are movable in a direction approximately parallel to the disk axis.

The oscillatory lever 31 carries thereon a weighted centrifugally actuated member 38 which is shiftable with respect to the lever to insure satisfactory operation of the switch throughout a wide range of speed-settings. The centrifugally actuated member is preferably in the form of an auxiliary lever of angular shape which is mounted intermediate its ends on the oscillatory lever 31, as by means of a cross shaft 39 extending parallel to the hinge axis of the oscillatory lever and having reduced ends journalled in bearing members 40 secured to the fork arms of the oscillatory lever. The auxiliary lever 38 extends radially of the disk axis and is movable in the space between the fork arms of the lever 31 and in the gap 28 between the ends of the C-shaped frame 27. The axis of the cross shaft 39 extends in the region between the disk axis and the contacts. The outer end of the auxiliary lever 38 carries an off-center weight member 41 which extends angularly in a direction away from the insulating disk and which is secured to the lever by rivets 42, one of these rivets also serving to lock the cross shaft 39 to the weight member. The inner end of the auxiliary lever 38 is disposed at the axis of the disk and carries a rounded metal button 43 against which is adapted to bear the rounded insulating tip 44 of an adjusting screw 45, the latter extending axially of the disk and movable in the central open space of the C-shaped frame 27. In order to permit adjustment of the screw while the switch is operating, the screw is carried in a stationary screw-threaded support 46. Inward movement of the inner end of the auxiliary lever 38 is yieldingly resisted by a leaf spring 47 which extends in a radial direction and has its outer end riveted or otherwise secured to the hinged end portion of the oscillatory lever 31, the inner end of the spring 47 having an embossed rounded end which bears on the inner side of the button 43. The spring 47 holds the button 43 against the tip 44 of the adjusting screw 45, and the inward displacement of the spring by the screw serves to counteract the biasing force of the hinge spring 34.

The centrifugal switch may be used in any suitable circuit and by way of example it is here shown to be included in series with motor windings comprising a pair of series field windings 48 and an interposed armature 49, the field windings being connected to line conductors 50. The brush 23 is connected by a conductor 51 to one of the motor brushes and the brush 24 is connected by a conductor 52 to one end of one of the field windings 48, thus placing the centrifugal switch in series with the motor windings. In some instances the switch is shunted by a resistor 53 and by a protective device such as a condenser 54. By placing the switch in circuit between the field windings, the latter will form choke coils or reactors in both line conductors to prevent or minimize the transmission to these conductors of electrical disturbances that may be caused by the operation of the switch. The motor windings may be those of the motor 16 or of a separate motor.

When the centrifugal switch of Figs. 1 to 6 is at rest the contacts 37 are urged by their spring-mounted supporting lever 31 into engagement with the contacts 28 carried on the frame 27. The contact engagement will be maintained throughout the normal range of adjustment of the speed-setting screw 45. For adjusting the switch to open at a high speed the screw is turned

outwardly to the position shown in Fig. 1, thus causing the weighted lever 38 to turn counter-clockwise (as viewed in Fig. 1) under urge of the spring 47 and reducing the effective force arm of the weight 41 with respect to the cross shaft 39. Upon setting the motor shaft 15 in rotation the centrifugal force on the weight 41 will tend to turn the auxiliary lever 38 counter-clockwise (as viewed in Fig. 1) about the cross-shaft 39, and since the lower end of the lever 38 bears on the adjusting screw 45 there will be an inward pressure on the contact-carrying lever 31, opposing the pressure of the hinge spring 34 and tending to separate the lever contacts 37 from the frame contacts 28. Upon the attainment of a certain critical shaft speed, determined by the resilience of the hinge spring 34 and force arm of the weight 41, the centrifugal turning moment produced by the weight 41 will become sufficient to move the lever 31 inwardly and cause the lever contacts 37 to move out of engagement with the frame contacts 28. As a result, the electric circuit through the brushes 23 and 24 will be interrupted by the separation of these contacts. If it is desired to have the centrifugal switch operate at a lower speed-setting, the screw 45 is turned inwardly, as to the position seen in Fig. 6, causing the weighted lever to swing clockwise (as viewed in Fig. 6) and inwardly flexing the spring 47. The contacts will then separate at a somewhat lower critical speed determined by the reduced effective force of the hinge spring 34 and the increased force arm of the weighted lever 38. By turning the screw 45 inwardly from the position of Fig. 1 to the position of Fig. 6, the speed-setting of the switch will be progressively reduced through a wide range. If the screw is moved inwardly a sufficient distance, the lever contacts 31 will remain separated from the contacts 28, even when the switch is at rest, and if the screw is moved outwardly a sufficient distance, the contacts will remain in engagement regardless of the speed of the shaft. In the latter case the force arm of the weight member 41 will be zero or very small.

In the arrangement shown in Fig. 1, the centrifugal switch is employed to control the series-type electric motor 16 by which it is driven. As soon as the motor accelerates to the critical speed, the contacts 28 and 37 separate, thereby introducing the resistor 53 in series with the motor windings. The motor speed then drops slightly below the critical speed, whereupon the contacts 28 and 37 again engage to cause the motor speed to increase. In practice, the oscillatory contact-carrying lever 31 of the switch vibrates at a relatively high frequency, and as a result the adjusted motor speed remains substantially constant.

It will be noted that the speed-setting of the centrifugal switch is affected by two factors, one the variation of the effective spring action on the oscillatory contact-carrying lever 31 and the other the variation of the effective force arm of the centrifugally actuated weighted lever 38. As a result of these two factors, and especially the latter, the switch will operate in a satisfactory manner over a wide range of speed adjustments. At high speeds the effective spring action is relatively strong and the effective force arm of the weighted lever 38 is relatively short, thus avoiding excessive centrifugal action. At low speeds the effective spring action is relatively weak and the effective force arm of the weighted lever 38 is relatively long, thus obtaining

a favorable centrifugal action on the weighted lever.

The plate-like contact-carrying members of the switch extend in planes approximately normal to the shaft axis, thus providing for efficient cooling of the off-center contacts without excessive windage losses. The construction of the switch readily permits the use of a plurality of contact pairs so as to provide adequate current-carrying capacity, and the contacts can be easily replaced if necessary. The switch is of such construction that it can be economically manufactured, the parts thereof being capable of inexpensive fabrication and easy assembly.

In the modified form of centrifugal switch shown in Figs. 7 and 8, the pivot shaft 39 and spring 47 of Fig. 2 are omitted, and the weighted lever 138 (corresponding to the lever 38) is hingeedly carried on the forked oscillatory lever 31 by springs 139. The springs are here shown to be leaf springs of E-shaped configuration, the free ends of the outer arms of the springs being secured by short riveted posts or studs 140 to the oscillatory lever, and the free ends of the intermediate arms of the springs being secured to side extensions 138' of the weighted lever. The connecting bars of the E-shaped springs are in alignment and extend transversely of the oscillatory lever. The angular displacement of the weighted lever 138 by the adjusting screw 45 is yieldingly resisted by the hinge springs 139. The construction and operation of the switch of Figs. 7 and 8 are otherwise the same as that of Figs. 1 to 6.

The modified form of centrifugal switch shown in Fig. 9 is generally similar to that of Figs. 1 to 6 except that the contacts have been reversed so as to be normally open, thus adapting the switch to be used in various circuits requiring this contact relation. For this purpose the contacts 29 are reversed on the spring-mounted oscillatory lever 31 to face the insulating disk 19 and to engage cooperating contacts 137 detachably mounted on a flat annular supporting frame 127 secured to the disk 19 and outer collector ring 21 by spacing studs or posts 125 and associated screws 126. The studs 125 correspond to the studs 25 of Fig. 3, and the frame 127 corresponds to the plate 27 of Fig. 3. The contacts 29 and 137 of the switch of Fig. 9 are normally open, and upon attainment of a critical shaft speed, the centrifugally actuated weighted lever 38 causes the contacts to engage. The construction and operation are otherwise the same as that of the switch of Figs. 1 to 6. The modification shown in Fig. 9 may also be applied to the switch of Figs. 7 and 8.

Certain embodiments of the invention have been shown and described, but it will be obvious to those skilled in the art that modifications may be made without departing from the spirit and scope of the invention.

What I claim as new and desire to secure by Letters Patent is:

1. In a centrifugal switch, the combination of a rotatable member, a contact carried by said member, a lever swingably mounted on said member and movable in a generally axial direction with respect to said member, said lever being spring-urged in one direction, a contact carried by said lever and cooperating with said first-named contact, a weight member having a pivotal mounting on said contact-carrying lever to swing about an axis transverse to the axis of said

rotatable member and centrifugally actuated to urge said contact-carrying lever in a direction opposite to its spring-urged direction, means for angularly displacing said weight member with respect to said contact-carrying lever to adjust the effective arm of force of said weight member with respect to said lever, and resilient means normally urging said weight member in a direction reducing said arm of force.

2. In a centrifugal switch, the combination of a rotatable member, a contact carried by said member, a lever swingably mounted on said member and movable in a generally axial direction with respect to said member, said lever being spring-urged in one direction, a contact carried by said lever and cooperating with said first-named contact, a weight member having a pivotal mounting on said contact-carrying lever to swing about an axis transverse to the axis of said rotatable member and centrifugally actuated to urge said contact-carrying lever in a direction opposite to its spring-urged direction, means for angularly displacing said weight member with respect to said contact-carrying lever to adjust the effective arm of force of said weight member with respect to said lever, and resilient means normally urging said weight member in a direction reducing said arm of force, said resilient means being carried on said lever to reduce the biasing force on said lever when the arm of force of said weight member is increased.

3. In a centrifugal switch, the combination of a rotatable member, a contact carried by said member, a lever swingably mounted on said member and movable in a generally axial direction with respect to said member, said lever being spring-urged in one direction, a contact carried by said lever and cooperating with said first-named contact, a weight member having a spring hinge connection with said lever to swing about an axis transverse to the axis of said rotatable member and centrifugally actuated to urge said lever in a direction opposite to its spring-urged direction, and means for angularly displacing said weight member with respect to said lever to adjust its effective arm of force with respect to said lever, said spring hinge connection normally urging said weight member in a direction reducing said arm of force.

4. In a centrifugal switch, the combination of a rotatable member, a contact carried by said member, a lever swingably mounted on said member to move in a generally axial direction with respect to said member, said lever being spring-urged in one direction, a contact carried by said lever and cooperating with said first-named contact, a centrifugally actuated weight member pivotally carried by said lever for urging said lever in a direction opposite to its spring-urged direction, the pivotal axes of said weight member and lever being generally parallel and extending transversely of the axis of rotation of said rotatable member, and means for angularly shifting said weight member with respect to said lever to adjust the arm of force of said weight member and to thereby adjust the speed setting of the switch.

5. In a centrifugal switch, the combination of a rotatable member, contacts carried by said member, a lever swingably mounted on said member to move in a generally axial direction with respect to said member, said lever being spring-urged in one direction and having forked free end portions forming an opening between them, contacts carried by the forked portions of

the lever and cooperating with said first-named contacts, a centrifugally actuated weight member pivotally carried by the forked portions of the lever and movable in said opening, and means for angularly shifting said weight member with respect to said lever to adjust the arm of force of said weight member and to thereby adjust the speed setting of the switch.

6. In a centrifugal switch, the combination of a rotatable member, a frame mounted on said member and having an opening, contacts carried by said frame on opposite sides of said opening, a lever swingably mounted on said member to move in a generally axial direction with respect to said member, said lever being spring-urged in one direction, contacts carried by said lever and cooperating with said first-named contacts, and a centrifugally actuated weight member mounted on said lever for urging said lever in a direction opposite to its spring-urged direction, said weight member being movable in the opening of said frame.

7. In a centrifugal switch, the combination of a rotatable member, a contact carried by said member, a lever swingably mounted on said

member to move in a generally axial direction with respect to said member, a contact carried by said lever and cooperating with said first-named contact, said lever being spring-urged in a direction to effect disengagement of said contacts, a centrifugally actuated weight member shiftably carried on said lever for urging said lever in contact-closing direction, and means for shifting said weight member with respect to said lever to adjust the arm of force of said weight member and to thereby adjust the speed setting of the switch.

8. In a centrifugal switch, the combination of a rotatable member carrying a pair of contacts, resilient biasing means for one of said contacts, centrifugally actuated means carried by said member for relatively displacing said contacts and including a shiftably mounted weight member having a variable arm of force, resilient means normally urging said weight member in a direction reducing said arm of force, and means to adjust said arm of force to thereby vary the speed setting of the switch.
